UNITED STATES PATENT OFFICE.

GUSTAV BEHM, OF CHICAGO, ILLINOIS.

EXTENSION-TABLE.

No. 830,042.

Specification of Letters Patent.

Patented Sept. 4, 1906.

Application filed March 27, 1905. Serial No. 252,111.

To all whom it may concern:

Be it known that I, GUSTAV BEHM, a citizen of the United States, residing at Chicago, in the county of Cook and State of Illinois, 5 have invented certain new and useful Improvements in Extension-Tables, of which the following is a specification.

This invention relates to improvements in extensible tables; and the especial object of 10 my improvements is to produce a table of this type that will be free from supporting-legs, and especially in which there will be no legs moving with the extended portions.

A further object is to provide a construction from which will be omitted the more or less complicated adjusting and controlling mechanism that is characteristic to most tables of this class and at the same time furnish a table that can be quickly and easily 15 adjusted and that will be ornamental and conform to the general design of popular dining-tables.

In the accompanying drawings, which form a part of this application, I have illustrated a preferred application of my invention in the following views:

Figure 1 is a side elevation of a table made according to my invention and shown in its closed position. Fig. 2 is a side elevation 20 showing the table partially extended. Fig. 3 is a side elevation showing the table fully extended and with a portion broken away. Fig. 4 is a bottom plan view of the table-top, the supporting-standard being removed. 25 Fig. 5 is a transverse section through the table-top and the upper part of the supporting-standard. Figs. 6 and 7 are details in perspective, on an enlarged scale, of rails which form elements of construction in my 30 improved table. Fig. 8 is a fragmentary detail showing the method of guiding the extensible part of the table-top.

Referring to the drawings in detail, A represents a supporting-standard built in the 35 rectangular form shown and resting on a base a' , which in turn is supported by the claw-feet a^2 , the latter being preferably of metal, so as to add to the weight of the standard, and thus make it more effective as a support for 40 the table-top to be described. The standard is hollow and divided into two chambers a^5 a^6 by a horizontal shelf a^4 , to which access is had by a hinged door a^3 . To the top of the 45 standard, on two sides thereof, are secured lateral braces a^8 , which extend transversely

to the top of the table and serve as an additional support for the parts to be described.

Extending longitudinally of the table-top and secured to the braces a^8 are two pieces B B, which serve in part to support the table-top and furnish a slideway and guide for the outer slide-rails d d . Other longitudinal pieces e e are also rigidly secured to the braces a^8 a^8 and form a guide and slideway for the inner slide-rails d' d' . The strips e are connected at their ends by cross-pieces e' , which serve, in connection with the pieces e e , as a support for the table-top. The slide-rails d d' , which are arranged between the longitudinal pieces B and e , are spaced apart and 60 along their adjacent or opposite faces have secured thereto rack-bars d^4 d^5 , respectively, the former being secured to the rails d and the latter to the rails d' , as clearly shown in Figs. 5 and 6. Extending transversely 65 through the pieces e , d , d' , and B and arranged centrally of the standard A is a shaft F, the opposite ends of which are squared, as at f^3 , to receive an operating key or crank f^5 . (Shown in Fig. 2.) Mounted on this shaft 70 between each pair of slide-rails d d' is a pinion f^4 , which meshes with the rack-bars d^4 d^5 and upon being rotated through the rotation of the shaft cause the slide-rails to move in 75 opposite directions to each other. The shaft F, in addition to having suitable bearings in the pieces e and B, is also journaled in the hanger-blocks f' , which are secured to the under side of the table-top C. Between 80 these hangers there is mounted on the shaft F a spool f^2 , on which are secured the inner ends of straps f^6 , said straps being made from suitable elastic webbing, and their outer ends are connected with the end slats c^2 of the slatted or curtain portion of the table-top, 85 thus maintaining a tension on said slats at all 90 times.

The table-top C is made up of boards which are rigidly secured together and form the permanent or fixed portion of the top and of 95 slats, as c' c^2 , which are narrow wood strips connected together by canvas c^3 in the manner usual in forming wood curtains. Some of the slats c' have inserted in their under side pins c^4 , formed with round heads, which are 100 adapted to slide or move through the slots d^2 d^3 , formed longitudinally through the upper and lower sides of the slide-rails d d' , respectively. The rails d d' are further provided 105 with longitudinal slots d^6 , through which ex- 110

tend the shaft F, thereby permitting the longitudinal movement of said slide-rails, as will be readily understood. The ends of the slide-rails d are rounded, as at d', to facilitate the 5 turning of the slats around same in the operation of the slatted or curtain portions of the table-top.

A table constructed substantially as above described and normally in its closed position, 10 as shown in Fig. 1, can be extended by applying the crank f⁵ to either end of the shaft F and turning same, thereby sliding each pair of rails d d' in opposite directions. The tension of the straps f⁶ will be sufficient to hold 15 the slats closely to the under side of the slide-rails and also facilitate their movement, but will not be sufficient to overcome the friction between the slide-rails and their adjacent parts, so that the extensible portions of the 20 table-top will always remain where they are left by the operator. When the usual cloth or mat is over the top of the table, the open joints at the ends of the top will be covered, so that there can be no objection to same.

25 It will be seen that in my improved table the base and standard are always at the center and that there are no supports or legs moving with the extensible portions. The compartments a⁵ a⁶ are suitable receptacles for

table accessories, or, if desired, a single compartment could be used to receive a metal safe or strong-box in which silverware could be stored.

Having thus described my invention, what I claim as new, and desire to secure by Letters Patent, is

In a table, a centrally-disposed supporting-standard, rails fixed on said standard, and other rails slidably supported on said standard, and having grooves formed therein, rack-bars secured to said slide-rails, a shaft extending transversely through said fixed and slide rails, pinions fixed on said shaft and meshing with said rack-bars, a spool fixed on said shaft and having elastic straps secured thereto, 45 a table-top composed of boards rigidly secured to said fixed rails, and of extensible sections formed of slats flexibly connected together and with the said boards and connected with said elastic straps, pins fixed in 50 said slats and adapted to slide in the grooves in said slide-rails.

In testimony whereof I affix my signature in presence of two witnesses.

GUSTAV BEHM.
